WALTER J. CLARK, OF CHICAGO, ILLINOIS, ASSIGNOR TO COE LABORATORIES INC., OF CHICAGO, ILLINOIS, A CORPORATION OF ILLINOIS

INVESTMENT VIBRATOR

Application filed June 5, 1931. Serial No. 542,457.

This invention relates generally to a vibrator, and particularly of a type adapted for use particularly with dental investments. In the ordinary method of constructing molds for dental plates, inlay fillings, and other oral restorations it is usual to form a wax pattern by impressing it into the cavity to be filled, in the case of inlay fillings for example, and to apply to that pattern some form of thin primary coating of dental investing material for the purpose of securing a smooth casting, followed by an investment of coarser or stronger material. It is essential that this thin primary coating of dental investing material be very uniformly applied, and in the past it has been usual to apply these primary coatings a small amount at a time, gently shaking or tapping the wax pattern on some stationary object to secure a smooth application.

It is also necessary in finally settling the wax pattern in the investment material to vibrate the same in order to drive out air bubbles and to secure a dense mold. For this purpose vibrating machines are used. The machines heretofore used have been quite noisy, and when placed upon a table or on a dentist's work bench have produced considerable vibration and rattling.

It is one of the objects of the present invention to provide a vibrating machine which is so constructed as to be substantially noiseless and which transmits no vibrations to the table or bench upon which it rests. This is accomplished, in the embodiment of the invention herein illustrated, by mounting the vibrator unit in a rather heavy base. The high inertia of the base prevents vibration thereof at the rather high frequency of vibration of the vibrator.

Another object is the provision of a vibrating device which is conveniently portable and in which attachment to a work bench, table or the like is eliminated.

It is a further object of the present invention to provide a vibrator of the class described with a vibrating disk so constructed that vibrations varying from an almost imperceptible movement to violent tappings may be obtained. The disk is made pref-

erably of rubber, although other substances may be used, and is thickest at the center and very thin at the rim. If an object is held against the vibrating disk at the rim the object is vibrated lightly, the magnitude of the vibrations increasing as the object is brought closer to the thick center portion of the disk.

Other objects and advantages of my invention will appear to those skilled in the art after a consideration of the following description read in conjunction with the accompanying drawing in which:

Figure 1 is a top plan view of my improved vibrator.

Figure 2 is a sectional view taken on the line 2—2 of Figure 1, the vibrator being shown in elevation.

Figure 3 is a sectional view taken on the line 3—3 of Figure 1, and showing an investment bowl in position to be vibrated.

A heavy base member 1 is provided with an interior recess or chamber 2 which is open at the bottom, and a thickened or widened bottom portion 3 sloping outwardly from each side of the base member, the latter construction materially increasing the weight and inertia of the heavy base member.

The base member 1 is provided with an aperture 4 through which extend the leads 5 which are connected to a switch mechanism 6, shown in Figure 2 as of the usual tumbler type. Mounted within the recess 2 is a magnet coil 7 having an iron core 8, said coil being connected to the switch 6. The magnet is provided with an armature 10 resiliently mounted, as by a spring member 11, in proximity to the poles of the iron core. Fixed to the armature 10 is a threaded stem 12 extending upwardly through an aperture 13 in the top part of the base member 1.

A vibrator disc 14 of rubber or other suitable elastic material is provided with a pin 15 having a head embedded therein and a threaded extension received within and carried by the stem 12. As is clear from Figure 3 the vibrator disc 14 is provided with a thin peripheral edge 16 and a thickened central portion 17, for a purpose to be described later. The vibrator disc is concave slightly

so as to be able to hold objects thereon by suction. The base member 1 is provided at the corner thereof with rubber foot members 18 which serve as cushion supports for the base member. The coil 7 is secured to the base member 1 by an angle plate 19 and screws 20.

In the normal operation of my device the leads 5 are connected to a source of alternating current so that when the switch 6 is actuated to close the circuit, the armature 10 will be set into vibration. The rubber vibrator disc 14, which is carried by the armature 10, will be correspondingly vibrated, and hence any object placed thereon will be also vibrated.

For example, Figure 3 shows a hard rubber bowl 21 carried by the vibrator disc 14 and containing a mass of investment plaster 22. Preferably, the plaster and bowl is shaken first by hand and then placed on the vibrator disc 14 for a final vibration whereby the plaster is compacted and freed of air bubbles.

In the case of inlay fillings the wax inlay pattern is mounted on a sprue former, and after the pattern is given an initial application of the primary investing material it is held in contact with the vibrator button 14 so as to be vibrated thereby in order that the investing material may be spread uniformly over the pattern. This investing material is applied in the form of a powder or a paint. In cases where only light vibrations are desired, the wax pattern and attached sprue former are held in contact with the extreme peripheral edge of the vibrator disc. This edge, as described above, is thin so that the vibrations transmitted are light. In cases of larger patterns, for example, where it is desired that the vibration should be comparatively heavy, the pattern is held in contact with the vibrator disc at the central portion thereof, this being the thickened part referred to above.

Figure 2 shows how an inlay pattern 23 with sprue former 24 can be held against the edge of the disc 14 and receive light vibrations therefrom.

This feature of being able to apply to the pattern either light or heavy vibration is of great importance in this art, since there is little possibility of knocking loose these sprue formers. It is clear that by shifting these patterns from the center to the edge of the vibrator disc 14 any desired degree of vibration may be had. Obviously, if alternating

current is not available direct current from any suitable source may be employed, providing some form of self-interrupting circuit controlled by the armature is used.

It will be understood by those skilled in the art that any modifications of my invention may be constructed without departure therefrom. Therefore, I do not intend to limit myself to the specific modification described except as pointed out in the following claims.

I claim:

1. A vibrator comprising a heavy base member having integral top and side walls, the top wall having an opening therethrough and the latter being thickened along the lower portions thereof to increase the weight of the base member, vibrator mechanism mounted within the base member and including an armature disposed generally above the thickened portions of the side walls and having a portion projecting upwardly through the opening in said integral top wall, a flexible disc mounted on said projecting portion and having a varying cross-section whereby variation in intensity of vibration is produced at different points on the surface of the disc, and foot portions carried by the thickened sections of said side walls.

2. A vibrator comprising a base member having an interior recess, vibrating mechanism mounted in said recess, said mechanism having a projecting portion extending through the top of said base member, and a flexible disc secured to said projecting portion, said disc having a thickened central portion for transmitting relatively heavy vibration and a thin peripheral portion for transmitting relatively light vibrations.

3. A vibrator comprising a base member having an interior recess, vibrating mechanism mounted within said recess including an electromagnetically actuated member having a projecting portion extending through said base member, a switch mounted in the side wall of said member for controlling said vibrating mechanism, a flexible disc having a thickened central section and a relatively thin peripheral section for transmitting relatively heavy and light vibrations, respectively, and a pin member embedded centrally in said disc and engaging in the projecting portion of said vibrating mechanism.

In witness whereof, I hereunto subscribe my name this 16th day of May, 1931.

WALTER J. CLARK.
